(57) **CLAIM**

The ornamental design for a dual pivot axis, dual magnification illuminated table mirror, as shown and described.

DESCRIPTION

FIG. 1 is a front perspective view of a dual pivot axis, dual magnification illuminated table mirror according to the present invention.

FIG. 2 is a front elevation view thereof.

FIG. 3 is a right-side elevation view thereof.

FIG. 4 is a rear elevation view thereof.

FIG. 5 is a left-side elevation view thereof.

FIG. 6 is an upper plan view thereof.

FIG. 7 is a lower plan view thereof.

FIG. 8 is an upper left perspective of the mirror of FIG. 1, showing the mirror in a first alternate configuration in which a mirror frame thereof is tilted upward about a first, mirror-frame pivot axis.

FIG. 9 is a perspective view of the mirror of FIGS. 1 and 8, showing the mirror in a second alternate configuration in which a mirror frame support yoke thereof is pivoted downward and forward about a second, mirror frame support yoke pivot axis from the vertical orientation shown in FIGS. 1 and 8 to a horizontal orientation.

FIG. 10 is a front elevation view of the mirror of FIG. 9.

FIG. 11 is a right-side elevation view of the mirror of FIG. 9; and,

FIG. 12 is a rear view of the mirror of FIG. 9.

The broken lines shown in the drawings are included for the purpose of illustrating environmental subject matter and form no part of the claimed design.
